United States Patent Office

Des. 185,818
Patented Aug. 4, 1959

185,818

VENTILATOR FOR BOATS OR THE LIKE

John Herman, Chicago, Ill.

Application March 27, 1958, Serial No. 50,202

Term of patent 14 years

(Cl. D62—3)

Fig. 1 is a perspective view of a ventilator for boats or the like showing my new design;

Fig. 2 is a top plan view;

Fig. 3 is a side elevational view;

Fig. 4 is a front elevational view; and

Fig. 5 is a rear elevational view.

I claim:

The ornamental design for a ventilator for boats or the like, substantially as shown.
